UNITED STATES PATENT OFFICE.

NORA GREENE CHRISTIANSEN, OF GARY, INDIANA.

DESIGN FOR AN EMBLEM OR INSIGNIA.

51,455.

Specification for Design.

Patented Nov. 6, 1917.

Application filed August 27, 1917. Serial No. 188,534. Term of patent 3½ years.

To all whom it may concern:

Be it known that I, NORA GREENE CHRISTIANSEN, a citizen of the United States, residing at Gary, in the county of Lake and State of Indiana, have invented a new, original, and ornamental Design for an Emblem or Insignia, of which the following is a specification, reference being had to the accompanying drawing, forming part thereof.

The figure is a plan view of an emblem or insignia showing my new design.

I claim:

The ornamental design for an emblem or insignia as shown.

NORA GREENE CHRISTIANSEN.
